UNITED STATES PATENT OFFICE.

EDWIN R. CAHOONE, OF NEWARK, NEW JERSEY.

COACH-PAD.

SPECIFICATION forming part of Letters Patent No. 235,506, dated December 14, 1880.

Application filed October 27, 1880. (No model.)

To all whom it may concern:

Be it known that I, EDWIN R. CAHOONE, of Newark, in the State of New Jersey, have invented certain new and useful Improvements 5 in Coach-Pads, of which the following is a full and exact description.

In the drawings, Figure 1 is a plan view of the top of the main plate and its parallel ribs and the channels on each side of the ribs to receive the leather, as hereinafter described. Fig. 2 is a plan view of the under side of the top plate. Fig. 3 is a cross-section through both plates at the terret-hole in their operative position of being locked into each other. Fig. 15 4 is a top-plan view of a part of the complete pad. Fig. 5 is a longitudinal section through the center of a part of the pad, complete from the terret in all its parts. Fig. 6 is a cross-section of a complete pad, showing the manner 20 of locking in the leather fastening by means of the upper and lower plates. Fig. 7 is a similar cross-section, showing the manner of using a part of the pad-bottom leather itself for the lock between the plates without 25 the use of a separate strip.

A shows the main plate of the pad, which is provided with four parallel longitudinal ribs, B B' B' B'. The outer ribs, B, may be a little higher than the inner ribs, B' B'. (See 30 Figs. 6 and 7.)

C are channels between ribs B and B'. These channels are of such size and shape as to just hold the bent-over leather and the downward-projecting rib of the top plate.

35 The ribs B' B' are connected by bridges D D' for the terret and pad-screw, and to secure adjustability of mountings.

E is the top plate, having on its under surface ribs G, which lock into the channels C, 40 so as to compress and retain the leather in the channel.

H is the top leather of the pad. I is the stuffing. L is the bottom leather of the pad.

Fig. 6 shows one mode of applying my invention, and Fig. 7 shows another.

In Fig. 6 lock-strips s, of leather, are stitched to the upper edges of the bottom leather, L, and these strips s s are then locked between the ribs of the plates A and E, so as to tightly 50 compress and draw the leather L into its proper place and retain it there.

t is the strip of binding sewed on at the joint of the leather L and strip s. The top leather is now applied and secured by terret and pad-screw.

In Fig. 7 the bottom leather is cut wider, and I dispense with the strips s s and lock the edges of the leather L directly between the ribs of plates A and E. Finish is given by means of the binding-strip t'. 55 60

Great cheapness, simplicity, and strength, and adjustability are secured by my improved mode of construction.

I claim as my invention—

1. The combination of the pad-plate A, having ribs B B and B' B', forming channels to receive the bottom leather, the bridges to receive the terret and pad-screw, a top plate provided with ribs to enter said channels, and the terret and pad-screw to bind the two plates 70 together, substantially as described. 65

2. The combination of the pad-plate A, having ribs B B and B' B', and bridges D D with the top plate, E, having ribs G, constructed and arranged substantially as and for the purpose 75 described.

3. The strips s s, in combination with plates A and E and bottom leather, L, as and for the purposes set forth.

4. In a harness-pad, the bottom leather, L, 80 secured between the plates A and E, and combined with a binding-strip, substantially as and for the purpose described.

5. The combination of plate A, plate E, and bottom leather, L, all constructed and arranged substantially as and for the purposes 85 set forth.

6. The combination of plates A and E, bottom leather, L, strips s and t, and top leather, H, as and for the purposes set forth. 90

7. In a harness-pad, the bottom plate, A, of substantially the cross-section shown, having its outer edges curved upwardly, and provided with bridges to receive the terret and pad-screw, in combination with a top piece 95 and the terret and pad-screws, substantially as described.

EDWIN R. CAHOONE.
